UNITED STATES PATENT OFFICE.

LESLIE T. PETERSEN, OF DENISON, IOWA.

BARN BATTEN AND PANEL STRIP.

Application filed November 14, 1927. Serial No. 233,097.

The present invention relates to building construction, and more particularly to a batten strip adapted for use in wall, roof or siding structures.

5 An object of the present invention is to provide a batten strip as an article of manufacture or an element of building material which is not only extremely economical in its manufacture and shipment, but which is 10 also easily handled by workmen without the exercise of any great amount of skill.

Another object of this invention is to provide a batten strip possessing the above characteristics and which at the same time 15 has the advantage of maintaining the crevices between boards closed even after the boards have become warped and shrunk incident to exposure to the weather and incident to subjection to moisture and heat, 20 and a batten strip which may be easily and quickly applied and which may be fitted and secured in place by nails or other common form of fastening means.

The invention further aims at the provision of a batten strip which is adapted to be secured in overlapping relation with respect to the adjacent edge portions of boards in the wall, roof or the like and which may be secured fixedly to but one of the adjacent 30 edge portions and permitted to move relatively to the opposite edge portion so as to maintain the crevice closed and at the same time permit of the relative movement of the edge portions of the boards.

35 With the foregoing and other objects in view, the invention will be more fully described hereinafter, and will be more particularly pointed out in the claim appended hereto.

40 In the drawings, wherein like symbols refer to like or corresponding parts throughout the several views,

Figure 1 is a perspective view of a portion of a wall structure showing batten strips 45 constructed according to the present invention applied thereto.

Figure 2 is a horizontal section taken through the same substantially on the line 2-2 of Figure 1.

50 Figure 3 is a fragmentary face elevation showing a slight modification of the batten strip as applied to panel boards, such as used in interior or wall construction, and

55 Figure 4 is a fragmentary enlarged horizontal section taken through the same on the line 4-4 of Figure 3.

Referring to the drawing, and first to the form of the invention shown in Figures 1 and 2, 10, 11 and 12 designate three boards of a wall or roof structure which may be 60 relatively rough lumber, and with the boards approximating a general size, the same being built into the wall structure with crevices 13 between the adjacent longitudinal edge portions of the boards. The batten strip 65 of this invention is adapted to be applied to the exterior of the wall in order to close or seal the crevices 13 against the entrance of wind, rain and the like, so as to effectively close the entire wall.

70 The batten strip comprises a flat body portion 14 of sheet metal which is of suitable gauge and composition to resist the elements and at the same time to impart to the strip the desired resiliency and stability in holding the strip to its original shape. The longitudinal edge portions 15 and 16 of the strip are bent to one side of the plane of the body of the strip 14 and at an obtuse angle 75 to the body of the strip so as to provide beveled edge portions to the strip with the free edges of the strip forming biting or close fitting edges adapted to engage against and be somewhat embedded in the outer surfaces of the adjacent boards of the wall 85 structure. The strips 14 are made of sufficient width to overlap the adjacent edge portions of the boards for a considerable extent, within practical limits, so that the boards may be permitted to move toward 90 and from each other to vary the width of the crevice 13 without leaving the bent edges or flanges 15 and 16 of the batten strip.

95 In order to permit of the free movement of the boards toward and from each other without splitting or damaging the boards and still retain the batten strip 14 in proper position, the batten strip is provided near one longitudinal edge or flange, such as 15, with a row of longitudinally spaced 100 apart openings 17 adapted to receive nails 18 or other suitable fastening devices which are adapted to be secured into one of the boards only at one side of the crevice 13. The other side of the batten strip 14 is left 105 free and the inherent resiliency of the strip 14 is relied upon to maintain the flange 16 in surface contact with the opposite board of the wall. The boards may thus move toward and from each other and the flange 110 16 merely slides over the outer surface of its adjacent board. The openings 17 are

spaced sufficiently from the flange 15 to not only maintain the edge of the flange 15 in surface contact with the adjacent board, but to also impart the desired leverage or purchase of the batten strip with its flange 16 against the opposite board.

In order that the batten strip 14 may be utilized in securing the panel boards 19 in position on interior walls and the like, the strip 14 is provided, as shown in Figures 3 and 4, with a longitudinal row of spaced openings 20 which are positioned intermediate the flanges 15 and 16 so that nails 21 or other suitable fastening devices may be secured through the batten strip 14 and through the crevice 22, which is formed between the adjacent edge portions of the panel boards 19. In interior work, the panel strips 19 are not subjected to the severe climatic changes to which the exterior boards of a wall or roof are subjected and consequently the shrinkage or displacement of the edge portions of the panel boards 19 is relatively small.

Again, the nails 21 being so positioned, as shown in Figures 3 and 4, engage in the frame structure 23 of the wall and do not engage either of the panel boards 19 so that the latter are free to expand and contract without distortion or cracking incident to any anchorage which they may have to the batten strip 14.

In the modified form shown in Figures 3 and 4 the batten strip is of the same construction as in the preferred form shown in Figures 1 and 2 so that the flanges 15 and 16 are held in surface contact with the panel boards 19 by the inherent resiliency of the batten strip 14.

It is apparent that in the form shown in Figures 1 and 2 the batten strips may be easily and quickly applied by securing the same at one edge portion of each board 10, 11 and 12 and that the strips 14 will thus be held firmly in place and in surface contact with the edge portions of both of the

adjacent boards. If desired, the batten strips may be secured to the boards prior to the positioning of the boards in the wall or roof structure as the boards may then be successively fitted into place with the projecting edge portions of the batten strips against the free edge portions of the boards which have already been secured in place.

In the form shown in Figures 3 and 4 the panel boards 14 may be fitted against the wall with a slight crevice 22 between them and the nails 21 then driven into place. Of course, these batten strips may be used in fence structures, in the building of barns as in the side walls and roofs thereof, or may be used in various other building structures both on the interior and on the exterior.

It is obvious that various changes and modifications may be made in the details of construction and design of the above specifically described embodiment of this invention without departing from the spirit thereof, such changes and modifications being restricted only by the scope of the following claim.

What is claimed is:—

A batten strip comprising a long relatively flat body portion adapted to overlap the crevice between the adjacent boards in a wall, and having its longitudinal edge portions bent inwardly at a slight angle to provide beveled edges and surface engaging portions adapted to seal the batten strip against the adjacent boards of the wall, and to space the body portion of the batten strip from the board, said body portion of the batten strip having a longitudinal row of spaced apart nail receiving openings through which may pass nails for securing the batten strip against said boards and with at least one edge of the batten strip freely slidable over the surface of the adjacent board of the wall.

In testimony whereof I affix my signature.

LESLIE T. PETERSEN.
